UNITED STATES PATENT OFFICE.

SAMUEL CROMPTON, OF BELFAST, IRELAND, ASSIGNOR OF ONE-HALF TO ARTHUR GREGG, OF BELFAST, IRELAND.

DEVICE FOR REMOVING AND FASTENING THE RIVETS SECURING THE KNIVES OF REAPING AND LIKE MACHINES.

1,299,134.

Specification of Letters Patent. Patented Apr. 1, 1919.

Application filed December 7, 1917. Serial No. 206,009.

To all whom it may concern:

Be it known that I, SAMUEL CROMPTON, of Belfast, Ireland, a subject of the King of Great Britain and Ireland, have invented a 5 certain new and useful Device for Removing and Fastening the Rivets Securing the Knives of Reaping and like Machines, of which the following is a specification.

This invention relates to the cutting 10 knives, or teeth, of reaping machines and the like, and its object is to provide a quick and convenient tool, or device for removing the blunt knives from the knife bar, or back bar, and also for readily and conveniently 15 securing new knives thereon if desired.

The object of my invention is effected by providing a device having a straight edge, or fence bar, against which the front of the back bar or knife carrier is held so that the 20 knives lie on top of said fence with the knife bar against its back edge. Behind said fence I provide a tool carrying slide which is suitably supported and adapted to be reciprocated by suitable means toward and 25 away from the fence, so that, by pressing the tool forward the knife can be forced off the bar by shearing the rivets fastening it thereto. Preferably, the means for reciprocating the slide consists of a crank 30 and operating hand lever, the crank, which is supported in suitable bearings, engaging a slot, or opening, in the slide so that, when the crank is oscillated the bar will be reciprocated. At the front of the slide I provide the 35 tool for removing the knives from the knife bar, which tool is removable and capable of being replaced by another tool for securing the knives to the knife bar. For removing the knives the tool is so made that it fits over

40 the top and along the back edge of a knife, or tooth, behind a rivet, but is not deep enough to reach the top edge of the knife carrying bar, so that, when the tool is forced forward by the slide bar and against the 45 back edge of the knife, enough pressure will be exerted to cause the knife to be broken off the bar at the rivet. This operation is repeated at each rivet until the knife or tooth is free. The portions of the rivets remaining in the back bar can be readily removed by a punch secured to the slide bar 50

and suitably positioned, so that, by holding the back bar with its back edge downward with one side against the fence, the punch can be caused to press out each rivet. 55

Similarly, a riveting tool can be secured to the slide bar and be used for riveting new knives to a back bar.

If desired a plurality of tools can be secured to one slide bar for the purpose of 60 expediting the removal of the knives and rivets, or for securing more than one rivet in position at a time.

In order that the invention may be clearly understood I have hereunto appended explanatory drawings, whereon, 65

Figure 1 is a side elevation of the device, partly in section, and showing the back bar and tool in position for the removal of the knife. 70

Fig. 2 is a plan view corresponding to Fig. 1.

Fig. 3 is a front elevation.

Figs. 4 and 5 are, respectively, elevation and plan views of the knife removing tool. 75

Figs. 6, 7, and 8 are respectively, sectional, plan, and end views, of a rivet removing tool.

Fig. 9 is a section of part of the device showing a riveting tool ready to be pressed 80 forward to form a snap head on a rivet. This figure also shows an elevation of the knife *k* with its rivets.

In the example shown on the drawings the device has a projecting support or fence 85 bar *a* secured to, or forming a part of, the sole plate *b* on which a movable tool carrying slide *c* is supported and adapted to be reciprocated in a path at right angles to the aforesaid fence bar. The actuation of the 90 tool carrying slide *c* is obtained by means of a crank *d* supported in bearings *b*¹ on the sole plate *b*. This crank engages between upstanding ears *c*¹ on the slide bar *c* and is connected by a lever *f*, and link *g*, 95 with an operating hand lever *h*, fulcrumed at *h*¹. The slide *c* is shown in mid position. At the front end of the slide bar *c* the knife removing tool *i* is adjustably secured. This tool is shown in larger detail at Figs. 4 and 100 5 and it will be seen it is so made that it fits partly over the top and partly down the

back edge of a knife *k*, lying on the fence bar *a* with its back bar *k*¹ against the bar *a*. The part *i*¹ of the tool is not deep enough to reach the top edge of the bar *k*¹.
5 When the tool is forced forward, by the forward movement of the slide *c* operated by hand lever *h*, sufficient pressure is exerted on the back edge of the knife to cause it to be freed from the bar *k*¹ by breaking away, or shearing, the rivet at the part *x*. This operation is repeated at each rivet until the knife is free. The portions of the rivets remaining in the bar *k*¹ can then be forced out by means of the punching tool *l*, shown
10 in Figs. 6, 7 and 8, which replaces the tool *i* for this purpose. Similarly by fitting a holding block *m* (Fig. 9) on the fence bar *a* and securing a riveting tool *n* at the end of the slide *c* new knives *k* can be riveted on to
15 the knife bar *k*¹ which is arranged vertically as shown in Fig. 9.

Although I have shown only one tool on the slide bar *c*, I may, as already stated provide a plurality of tools on one slide bar for the purpose of expediting the work of removing the knives from, or securing them to, the knife bars.
25

The device may be made portable and be capable of being bolted or clamped to a
30 bench or table.

The device hereinbefore described will be

found of great service in the repair of farming machinery and implements.

Having now fully described my invention what I claim and desire to secure by Letters Patent is:—

1. A device for removing the blunt knives from the knife bars of reaping and like machines comprising a sole plate with upwardly projecting support for the knife bar thereon, a slide, a crank for reciprocating the slide, means for operating the crank, and a tool secured to the slide and reciprocated thereby to operate on the knife to remove it from the bar.

2. A device for removing the blunt knives from the knife bars of reaping and like machines comprising a sole plate, bearings on the sole plate, a crank shaft carried in said bearings, a slide, ears on the slide engaging the crank of said crank shaft, a tool on the slide, and lever and link means for rocking the crank shaft and reciprocating the slide to bring the tool into operative engagement with the knife to remove the latter from the bar.

In testimony whereof I affix my signature in presence of two witnesses.

SAMUEL CROMPTON.
